ELECTRIC CLOCK

Arthur William Haydon, Waterbury, Conn.

Application June 1, 1934, Serial No. 728,500

14 Claims. (CL. 58—26)

This invention relates to improvements in time-instruments; and particularly to improvements in that class of electrically driven time-instruments known as the "maintaining-power" type, which are normally driven synchronously by an electric motor, but upon failure of the power supply to the electric motor, may automatically operate for a considerable period of time from an auxiliary power device.

10 There is a large class of instruments, such as clocks, recording devices and switching devices, which utilize timing mechanisms either continuously or intermittently in the course of their operation. Such instruments may be referred to as "time-instruments"; and their driven elements, such as the clock hands, recording drums, and switching drums or any part thereof, may be referred to as a "time-element". It has been found advantageous in many applications to drive such time-instruments by means of electric motors operating from an electric power supply such as a standard distribution circuit.

However, the usefulness and reliability of time-instruments which are operated solely by electric motors, is greatly impaired by the fact that the time-elements of such instruments do not function during interruptions of the electric power supply. Though such interruptions are not generally long in duration or frequent in occurrence, they are extremely objectionable. For example, if the instrument is a clock, unless it is reset by hand upon resumption of the electric power supply, the time indication will thereafter be inaccurate by an amount corresponding to the interval of current interruption; or if the instrument is a switching device, operation will be delayed by the same interval; or if a recording device, the record will be interrupted during that interval.

40 However, other features of electrically-driven time-instruments, such as their accuracy during normal operation and their freedom from any need for regulatory adjustments, have so strongly recommended their use that it has been proposed to provide such time-instruments with auxiliary power devices by means of which operation is maintained during interruptions of the electric power supply. Time-instruments having this feature are referred to as "maintaining-power time-instruments". In order that frequent inspection of the condition of the auxiliary power devices in such instruments shall not be necessary, it has also been proposed to provide means by which energy from the primary electric motor 55 may automatically be stored in the auxiliary

power device during normal operation, in order that such device may be kept in continual readiness to assume the burden of operating the instrument immediately upon interruption of the electric power supply to the primary motor. 5 Means have also been suggested by which the auxiliary power device shall automatically assume the driving function upon interruption of the primary power supply, and relinquish the driving function upon resumption of the primary 10 power supply.

In general, however, maintaining-power time-instruments heretofore proposed have been impractical because of their complexity of construction, with consequent mechanical unreliability and expense of manufacture. One difficulty has been the supposed necessity of providing a gear train for supplying energy to the auxiliary power device, and another gear train for discharging and regulating the discharge of the auxiliary 15 energy during interruptions of the primary power supply, in addition to the usual "synchronous" gear train through which the time-element is normally driven by the electric motor. It is an object of my invention to simplify the mechanism of maintaining-power time-instruments by providing such an arrangement of the several parts that a gear train forming a part of the mechanism through which power is normally transmitted from the electric motor to other parts of the instrument, may be utilized during operation from the auxiliary power device, thus eliminating the necessity for providing a separate gear 20 train for operation from the auxiliary power device. 25

The foregoing object may be accomplished by the provision of means by which a portion of the mechanism through which the time-element or driven member or mechanism is normally driven by the electric motor may be reversed upon failure of the electric power supply and serve as a driving train from the auxiliary power device. Means 30 may also be provided for regulating the operation of the auxiliary power device through said reversed gear train. 35

Another objection to many constructions heretofore proposed, is that the escapement provided for the regulation of operation from the auxiliary power device positively controls the movement even when the instrument is operating normally from the primary electrical supply; whereby are lost the great benefits of synchronous electrical operation. In other constructions in which the escapement exercises no positive regulatory function during operation of 40 45 50 55

the instrument from the primary electrical supply, it may be so coupled to the synchronous train that any serious maladjustment of the escapement causes injury to the escapement or 5 interferes with synchronous operation of the time-instrument. In constructions which obviate the above difficulties by providing for the entire disengagement of the escapement mechanism during synchronous operation, the condition 10 of the escapement mechanism may become impaired by disuse, or the quiescent condition of the escapement may render it somewhat slow in assuming its regular function when the primary power supply fails. It is an object of this invention 15 to provide a coupling through which the escapement mechanism may exercise a regulating function only when the instrument is operating from the auxiliary power supply, and through which the escapement mechanism may 20 be continuously agitated during normal operation, to keep the same in good working order for auxiliary operation.

With this object in view I provide an escapement coupling which is substantially unidirectional, in that it slips when the gear train is 25 driven in the normal direction by the electric motor, but transmits to the gear train a regulating torque when the gear train is driven in the reverse direction by the auxiliary power device. 30 Another object is to provide means for indicating to an observer whether the instrument is being operated from the primary electric power supply or from the auxiliary power supply. The means which I provide for accomplishing this 35 object comprises an element positioned outside the mechanism, but directly driven by that portion of the gear train which is reversed during operation from the auxiliary power device; thus, the indicating means shows by its direction of rotation whether the instrument is being driven by the motor or by the auxiliary power supply.

Another object is to provide in my improved arrangement means for automatically disconnecting the electric motor and other idle parts 45 from the mechanism during operation by the auxiliary drive. Thereby the load upon the auxiliary power device may be reduced and a longer period of operation therefrom made possible.

The various objects of my invention will be 50 more apparent upon considering the following detailed description of certain embodiments thereof. This description is to be taken in conjunction with the accompanying drawings in which:

55 Fig. 1 is a side elevation of a clock embodying my invention, the concentric arrangement of the shafts which bear the clock hands being shown in cross-section, and the escapement mechanism being omitted;

60 Fig. 2 is a vertical sectional view taken on the plane denoted by the line 2—2 of Fig. 1;

Fig. 3 is a horizontal sectional view taken on the plane denoted by the line 3—3 of Fig. 1;

65 Fig. 4 is the side elevation opposite that of Fig. 1, showing in section the escapement clutch;

Fig. 5 is a vertical sectional view taken on the plane denoted by the line 5—5 of Fig. 1;

70 Fig. 6 is a front elevation showing the parts in front of the front frame plate, a portion of the gears being broken away to show the relation of other gears therebehind;

Fig. 7 is a vertical sectional view taken on the plane denoted by the line 7—7 of Fig. 4;

75 Fig. 8 is an expanded diagram showing the

parts of the mechanism in their operative relationships;

Fig. 9 is an enlarged sectional view showing details of the arrangement of the concentric shafts which bear the clock hands;

Fig. 10 is an enlarged sectional view of the main spring and attachment, showing details of construction;

Fig. 11 is a sectional view taken along the plane denoted by the line 11—11 of Fig. 10, showing details of construction; and

Fig. 12 is an expanded diagram showing an alternative embodiment of my invention.

Similar numerals refer to similar parts throughout the several figures of the drawings.

The clock mechanism is supported by the usual front and rear frame plates 20 and 21, respectively, rigidly held in spaced relation by the columns 22. On the outside face of the rear frame plate 21 is attached the stator 23 of a synchronous 20 electric motor having a rotor 24 mounted on a shaft 25 which passes through an opening in the rear frame plate 21.

From the rotor shaft power is transmitted to the various elements of the mechanism through 25 suitable gear trains. Rigidly attached to the end of the rotor shaft 25 inside the rear frame plate 21 is the worm 26 which engages the worm wheel 27 attached to the arbor 28. Also attached to the arbor 28 is worm 29 which normally engages worm wheel 30 on the arbor 31. Secured to the arbor 31 are the collar 32 and the pinion 33, between which elements is the collar 34 loosely mounted on the arbor 31 so as to be rotatable with respect thereto. A spring 35 is 30 loosely wound about collars 32 and 34 in a manner hereinafter described in detail.

Attached to the collar 34 is the escapement wheel 36 with which may be associated any suitable escapement mechanism. Illustrated in Figs. 40 5, 7, and 8 is one such mechanism in which the wheel 36 is engaged by the detent member 37 pivoted at 38 and bearing a counterbalanced lever 39. One end of the lever 39 is bifurcated and embraces a pin 41 slightly offset from the balance 45 staff 40 at the center of the balance wheel 42. Associated with the balance wheel 42 is the usual hairspring 43 attached at its inner end to the balance staff 40 and at its outer end to the block 44 on the rear frame plate 21. Associated 50 with the hairspring 43 there may be provided any well known means to shorten or lengthen the effective length of the hairspring for regulating purposes.

The pinion 33 engages a gear wheel 44 attached to the arbor 45, to which are also attached the sweep-second hand 46 of the clock, the pinion 47, and the eccentric 48. The eccentric 48 is embraced by the prongs of a bifurcated element 49 attached to a rotatable shaft 50, which 55 passes through the front frame plate 20. Mounted on the shaft 50 outside of the front frame plate 20 is a rocker 51 having a pair of pawls 52, which successively engage the ratchet wheel 53 to rotate the minute and hour hands 54 and 55, respectively, of the clock through a suitable gear train comprising gears 56, 57, 58, 59, 60 and 61. The position of the clock face is indicated on Fig. 1 by the dotted element 77. The clock hands 46, 54 and 55, or any of them, may be 70 characterized as a time-element or as the driven member of a timing mechanism.

The auxiliary power device is a spring 68 which is connected to the pinion 47 through a suitable gear train comprising gears 62, 63, 64, 65 75

and 66. Gear wheel 66 is attached to the barrel 67 which is rotatably mounted on a shaft 69 rigidly attached to the frame plates 20 and 21. The inner end of the spirally wound spring 68 is secured to the shaft 69 in any suitable manner as by the pin 70. As shown in Figs. 10 and 11, the outer end of the spring 68 is provided with a slot 73 which engages a notch 74 in the connector 75. The connector 75 is rigidly attached to one end of the clutch band 76 and is movably engaged by a slot 72 in the other end of the clutch band. The clutch band 76 consists of a single loop of resilient material bowed into frictional contact with at least a part of the inner surface of barrel 67.

Means suitable for disengaging the rotor of the electric motor when the current fails are shown in connection with the worm 29 and worm-wheel 27 hereinbefore described. As illustrated in Figs. 1, 2, 3 and 4, these gears may be borne by an arbor 28 pivoted at its ends in a U-shaped member 79. The member 79 is supported by a pair of arms 80 pivoted on a pin 81 carried by a frame-member 82 attached to the rear frame plate 21. At the bottom of the member 79 is a projection 78 which bears upon the end of the shaft 25 under the tension of a spring 83 which is attached between the rear frame plate 21 and the projection 78.

30 The operation of the embodiment of my invention illustrated in Figs. 1 to 8 inclusive, is as follows:

The electric motor may be of any type which operates at a fixed speed commensurable with 35 the requisite speed of the device to be driven. Preferably, it is one of the self-starting synchronous type, which operates from an alternating current source having a frequency which is maintained very close to a fixed average value. 40 When the electric motor is energized, the rotor 25 bearing the worm 26 is driven at synchronous speed. Through a gear train comprising gears 27, 29, 30, 33 and 34, worm 26 drives shaft 45 in a clockwise direction at the rate of one revolution per minute. This rotation is indicated by the sweep-second hand 46 of the clock.

The revolution of the eccentric 48 with shaft 45 imparts to the bifurcated element 49 a cyclic oscillatory movement through a small arc. This 50 motion is transmitted through the shaft 50 to the rocker 51 which bears the double-acting pawls 52. These pawls being pivoted at opposite ends of the rocker 51, they alternately advance and recede, engaging the ratchet wheel 53 in succession to rotate it almost continuously. The movement of the ratchet wheel 53 is transmitted through the usual gear train comprising gears 56, 57, 58, 59, 60, and 61, to the minute and hour hands 54 and 55, respectively.

60 The important functional feature of this eccentric-and-ratchet mechanism is that it transmits to the clock-hands a clockwise rotation independent of the direction of rotation of the gear train which drives the eccentric. It is apparent that any other means which perform that function may be substituted for the mechanism shown.

The auxiliary power device for operating the instrument upon failure of the electric supply, may be any suitable energy-storing device, such as a spring or a weight system. In this embodiment, I have shown a suitable spring mechanism for the purpose. Here, the rotation of the pinion 47 serves to rotate the barrel 67 through the gear train comprising gears 62, 63, 64, 65, and 66. 70 As the barrel 67 is rotated the clutch band 76

is also rotated in the same direction because of its frictional engagement with the inside surface of the barrel. This movement of the clutch band 76 is transmitted through the connector 75 to the outer end of the spring 68. Since the inner end of the spring is fastened to the shaft 69 which is normally fixed against rotation, the rotation of the outer end in the driven direction winds the spring.

It is desirable to provide means to prevent 10 overwinding of the spring 68 during prolonged operation of the electric motor. The means shown in Figs. 7, 10, and 11 are suitable for this purpose. As the spring 68 becomes tightened, the outer end acts through the connector 75 to draw the ends of the clutch band 76 away from the inside surface of the barrel. This decreases the area of contact between the clutch band 76 and the inside surface of the barrel 67 until, when the spring is fully wound, the area of contact is so reduced that the clutch band slips on the inner surface of the barrel, thus preventing further tightening of the spring 68.

It is apparent that since the shaft 69 serves 20 no function in the operation of the timing mechanism, and is subject to a continual torque from the spring 68, means may be provided for periodically releasing the shaft 69 to operate a striking or alarm device of any common type.

Upon failure of the electric supply to the motor, the tension on the spring 68 almost instantaneously overcomes the inertia of the gear train comprising gears 66, 65, 64, 63, 62, 47, 44, 33, and 30, and causes the gear train to reverse its rotation. The reversal of the gear 47 on shaft 45 causes the sweep-second hand 46 to rotate in a counter-clockwise direction, thus indicating to any observer that the electric power has failed and the clock is then operating from the energy of the spring. However, this reversal of the 40 sweep-second hand does not affect the continued clockwise rotation of the minute and hour hands, because those elements are driven through the eccentric-and-ratchet mechanism previously described.

When the electric power supply fails, it is generally necessary to include in the mechanism some means for regulating the movement. Any well-known means for this purpose may be utilized, and I have shown a suitable lever escapement comprising the escapement wheel 36 co-operating with a detent 37, a counter-balanced lever 38, and a balance wheel 42 with a hair spring 43 and pin 41, operating in the usual manner.

To avoid any control by the escapement mechanism over the normal operation of the electric motor, I provide the novel clutch arrangement best shown in Figs. 4 and 8. The helical spring 35 is loosely wound about the collars 32 and 34 in such a direction that when the collar 34 is driven in the normal direction of rotation by the electric motor, the spring tends to loosen on the collars, allowing them to slip with respect to each other. The escapement wheel 36 may be constructed in such a way that it may be driven backwards; then, under the slight friction of the loosened spring the escapement wheel will slowly rotate backwards, keeping the detent and balance wheel in gentle agitation, ready to instantly assume a regulating function when the electric power supply fails.

When the electric power supply fails, the direction of rotation of the collar 34 is reversed, and the spring 35 then tends to tighten about 75

- the collars 32 and 34. The retarding effect of the detent 37 maintains the spring at a tension, locking the collars 32 and 34 together, and permitting the transmission of a regulating torque through the spring. It is thus seen that I have provided a coupling which is substantially irreversible in that it is incapable of transmitting a regulating torque except during reverse rotation of the gear train under auxiliary drive.
- 10 It is desirable to provide means for disconnecting the rotor of the electric motor and all other parts unnecessary to the operation of the clock by auxiliary drive, as quickly as possible when the electric power fails. The purpose is to 15 reduce the inertia of the mechanism so that it may be quickly reversed by the auxiliary power device, thus minimizing the time lost in the transfer. A further purpose in providing such means is to reduce the load driven by the auxiliary power device, thus prolonging the period for 20 which the auxiliary power device will operate following the failure of the electric power. Especially is it necessary to remove from operation all worm gears which are non-reversible. A 25 suitable means for accomplishing this purpose is shown in Figs. 1, 2, 3, and 4. In this device, when the stator of the electric motor is energized, it draws the rotor 24 forward as indicated by the arrow on Fig. 4. This axial displacement 30 of the rotor causes a corresponding displacement of the projection 78 which bears against the end of the shaft 25 on which the rotor 24 is mounted. The displacement of the projection 78 swings the suspension device forward to bring the gears 29 35 and 30 into engagement, as shown in Figs. 1 and 3, thus driving the synchronous gear train from the electric motor. However, when electric power fails, the suspension device and the rotor are drawn rearward by the spring 83 into the 40 position indicated by the solid lines in Fig. 4. This disengages the worm gears 29 and 30, removing them from operation until power is restored and the rotor draws forward into its normal position.
- 45 In Figs. 1 and 9 there is shown the concentric arrangement of the shafts which bear the clock hands and the gears 57, 58 and 61. A feature of this arrangement is the independent center 100 which consists of a hollow pin staked to the front frame plate 20, and carrying on its 50 inside the shaft 45 and on its outside the concentric shafts which bear the hands 54 and 55. To avoid excessive friction on the shaft 45, the 55 inside of the independent center may be made somewhat larger than the shaft 45 except at the forward end where a bearing is provided. The use of the independent center 100 lends 60 rigidity to the entire structure in front of the front frame plate 20, and prevents undue frictional load being placed on the shaft 45 by the other shafts. The latter advantage is of especial 65 importance when the clock is being driven by the auxiliary spring 68.
- From the foregoing description of the operation 70 of a clock embodying my invention, it is apparent that the entire gear train, with the exception of the worm gears 26, 27, 29 and 30, is utilized whenever the clock is in operation, whether driven by the electric motor or by the auxiliary power device. This construction dispenses with the duplicate gear train for auxiliary operation and makes possible a maintaining-power clock having only a few more parts than a clock not having the maintaining-power 75 feature, thus affording a marked contrast with

the complicated mechanism previously employed in such time-instruments. It will be noted that in the apparatus described above the gear train comprising gears 33 and 44 operates in one direction when driven by the motor and in the opposite direction when driven by the auxiliary power device.

Fig. 12 shows another embodiment of my invention in which 24' is the rotor of a synchronous electric motor driving a shaft 45' through a 10 gear train comprising gears 26', 27', 29', 30', 33', and 44'. Mounted on shaft 45' are the pinion 47', the eccentric 48, and the sweep-second hand 46, which correspond to similarly numbered parts of the embodiment previously described. 15 Eccentric 48 drives the parts numbered 49 to 61, inclusive, in the manner previously described. Pinion 47' winds the spring 68' through a gear 62' mounted on the shaft 69'. The barrel 67' in this embodiment is held stationary, except 20 when released to operate an alarm or striking device of some common type. In connection with the spring 68' may be provided suitable means to prevent overwinding, for example, means such as are shown in Fig. 10, above described. 25

A feature of this embodiment is the use of a regulator which is effective to limit the rate of operation of the clock when operated from the auxiliary power device, but which does not interfere with synchronous operation when the 30 clock is operated at normal speed by the electric motor. Such a regulator is the centrifugal device shown attached to the shaft 25'. It consists of a disk 90 attached to the end of shaft 25' and carrying a pair of magnetized fly-elements 92 pivoted eccentrically thereon at points 91, each fly-element being magnetized with a north pole and a south pole as shown in Fig. 12. Projecting from such fly-elements at points distant from the pivot points 91 are the pins 93 40 which are connected by the spring 94 which is attached at its center to a pin 95 at the center of disk 90. A stationary brake-band 96 of magnetic material such as soft iron surrounds the moving elements. Whenever the shaft 25' is 45 rotated in either direction, centrifugal force will cause the fly-elements 92 to swing outwardly about the pivot points 91, until the centrifugal force is balanced by the restraining force of the spring 94 as it is stretched by such outward 50 movement. The spring 94 is so adjusted that the fly-elements 92 do not quite engage the brake-band 96 when the device is rotating at its normal speed. Consequently, the device performs no 55 function during normal operation from the primary electric motor. However, when the instrument is operating from the auxiliary power device there may be some tendency to overspeed. Whenever such condition occurs, the increased centrifugal force causes the magnetized 60 fly-elements 92 to move outwardly to frictionally engage the brake-band 96 of magnetic material. There results a deceleration in the speed, but because of their magnetic adherence to the magnetic brake-band 96, the magnetized fly-elements 92 continue to adhere to the brake-band, until a speed slightly below normal is reached, at which point the fly-elements under the tension of spring 94 disengage the brake-band. The brake-band may be split and its 70 ends may be joined by a screw 97. By adjusting this screw the diameter of the brake-band 96 can be increased or decreased, thus regulating the speed at which the magnetized fly-elements will engage and disengage the brake-band. 75

The average speed over a period of time may by this means be kept approximately normal when the instrument is operating from the auxiliary power device.

5 In this embodiment it is seen that all of the parts are in operation whenever the clock is operating from either the electric motor or the auxiliary spring.

It is thus seen that the economy of parts and 10 simplicity of construction made possible by my invention may be accomplished by providing an arrangement by which at least a portion of the main driving gear train may be reversed upon failure of the primary power supply, and be utilized to perform driving and regulating functions 15 which have hitherto required auxiliary gear trains. Such an arrangement provides without any additional parts an indicator to show whether the device is operating from electrical 20 power or from the auxiliary power device. In such an arrangement, also, it is possible to solve the regulating problem simply by providing a coupling which effectively engages the escape- 25 ment mechanism only during operation of the gear train in the reverse direction under auxiliary drive. Further, it is feasible to provide an auxiliary power device which has only a single connection to the rest of the mechanism in that it both receives and discharges its auxiliary 30 energy through a single gear train.

My invention is not limited to the particular 35 embodiments thereof illustrated and described in detail herein, but includes such modifications thereof as fall within the scope of the appended 40 claims. For example, though I have specifically described a clock embodying my invention, it is apparent that my invention is equally applicable to other devices, such as recorders and time switches, which utilize a timing mechanism.

40 I claim:

1. In a device of the type described, a member 45 to be driven, an electric motor, means, including a gear train, arranged to drive said member in a single direction regardless of the direction of operation of said gear train, said gear train being normally driven in one direction by said motor to transmit power to said member and an auxiliary power device for driving said gear train in the reverse direction during cessation of operation of said motor.

2. In a device of the type described, a member 55 to be driven, an electric motor, means, including a gear train, arranged to drive said member in a single direction regardless of the direction of operation of said gear train, said gear train being normally driven in one direction by said motor to transmit power to said member, an auxiliary power device for driving said gear train in the reverse direction during cessation of operation 60 of said motor, said means being arranged to supply said auxiliary power device with energy from said electric motor during normal operation.

3. In a device of the type described, a member 65 to be driven, an electric motor, means, including a gear train, arranged to drive said member, said gear train being normally driven in one direction by said motor to transmit power to said member, said means also including means for imparting to said member a unidirectional rotation regardless of the direction of operation of said gear train, and an auxiliary power device for driving said gear train in the reverse direction during cessation of operation of said motor.

4. In a device of the type described, a member 70 to be driven, an electric motor, means, including

a gear train, arranged to drive said member, said gear train being normally driven in one direction by said motor to transmit power to said member, said means further including an eccentric-and-ratchet mechanism for imparting to said member a unidirectional rotation regardless of the direction of rotation of said gear train, and an auxiliary power device for driving said gear train in the reverse direction during cessation of operation of said motor.

5. In a device of the type described, a member 10 to be driven, an electric motor, means, including a gear train, arranged to drive said member regardless of the direction of operation of said gear train, said gear train being normally driven in one direction by said motor to transmit power to said member, means for automatically uncoupling said motor from said gear train upon cessation of operation of said motor and an auxiliary power device for driving said gear train in the reverse direction during cessation of operation of said motor.

6. In a device of the type described, a member 15 to be driven, an electric motor, means, including a gear train, arranged to drive said member in a single direction regardless of the direction of operation of said gear train, said gear train being normally driven in one direction by said motor to transmit power to said member, means associated with said gear train for regulating the speed thereof, and an auxiliary power device for driving said gear train in the reverse direction during cessation of operation of said motor.

7. In a device of the type described, a member 20 to be driven, an electric motor, means, including a gear train, arranged to drive said member in a single direction regardless of the direction of operation of said gear train, said gear train being normally driven in one direction by said motor to transmit power to said member, an auxiliary power device for driving said gear train in the reverse direction during cessation of operation of said motor and a rotatable indicator associated with said gear train whereby it rotates in one direction while said motor is operating and in the opposite direction during cessation of operation of said motor.

8. In a device of the type described, a member 25 to be driven, an electric motor, means, including a gear train, arranged to drive said member regardless of the direction of operation of said gear train, said gear train being normally driven in one direction by said motor to transmit power to said member, a regulating mechanism for regulating the operation of said gear train, an auxiliary power device for driving said gear train in the reverse direction during cessation of operation of said motor, and means responsive to the direction of rotation of said gear train for coupling said regulating mechanism to said gear train during operation of said gear train in the reverse direction.

9. In a device of the type described, a member 30 to be driven, an electric motor, means, including a gear train, arranged to drive said member regardless of the direction of operation of said gear train, said gear train being normally driven in one direction by said motor to transmit power to said member, a regulating mechanism for regulating the operation of said gear train, an auxiliary power device for driving said gear train in the reverse direction during cessation of operation of said motor, and means responsive to the direction of rotation of said gear train for coupling said regulating mechanism to said gear 35 train.

train during operation of said gear train in the reverse direction, said coupling means comprising a collar driven by said gear train, a collar positioned adjacent to said driven collar and coaxial therewith for driving the regulating mechanism, and a helical spring frictionally embracing both of said collars.

10. In a device of the type described, a member to be driven, an electric motor, means, including a gear train, arranged to drive said member in a single direction regardless of the direction of operation of said gear train, said gear train being normally driven in one direction by said motor to transmit power to said member, a regulating mechanism for regulating the operation of said gear train, an auxiliary power device for driving said gear train in the reverse direction during cessation of operation of said motor, and means for coupling said regulating mechanism 20 to said gear train during operation of said gear train by the auxiliary power device.

11. In a device of the type described, a member to be driven, an electric motor, means, including a gear train, arranged to drive said member in a single direction regardless of the direction of operation of said gear train, said gear train being normally driven in one direction by said motor to transmit power to said member, and an auxiliary power device including a spring, for driving said gear train in the reverse direction during cessation of operation of said motor, said gear train being connected to said auxiliary power device to wind said spring while said gear train is being driven by said motor.

35 12. In a device of the type described, a member to be driven, an electric motor, means, in-

cluding a gear train, arranged to drive said member in a single direction regardless of the direction of operation of said gear train, said gear train being normally driven in one direction by said motor to transmit power to said member, an auxiliary power device for driving said gear train in the reverse direction during cessation of operation of said motor, and a reversible driving connection between said gear train and said auxiliary power device, whereby energy is supplied to said power device from said electric motor during normal operation.

13. In a device of the type described, a member to be driven, an electric motor, means, including a gear train, arranged to drive said member, said gear train being normally driven by said motor to transmit power to said member, an auxiliary power device for driving said gear train during cessation of operation of said motor and a regulator for regulating said gear train, said regulator comprising a plurality of magnetized fly-elements centrifugally actuated by the rotation of said motor and a magnetic brake-band to frictionally engage said fly-elements when the speed of the device becomes higher than normal, and disengage said fly-elements when the speed of the device is reduced below normal by such frictional engagement.

14. A continuously rotating clock regulator comprising a magnetized fly-element, a spring centripetally restraining said fly-element, a brake-band of magnetizable material to frictionally engage said fly-element at speeds higher than normal and to disengage said fly-element when the speed has been reduced below normal.

ARTHUR WILLIAM HAYDON.
